CLAIM

The ornamental design for a packaging box as shown and described.

DESCRIPTION

FIG. 1 is a front elevation view of a packaging box showing our new design;

FIG. 2 is a rear elevation view thereof;

FIG. 3 is a left side elevation view thereof;

FIG. 4 is a right side elevation view thereof;

FIG. 5 is a top plan view thereof;

FIG. 6 is a bottom plan view thereof; and,

FIG. 7 is front and top perspective view thereof.

Broken lines shown in the drawings are for the purpose of illustrating parts of the article forming no part of the claimed design.

1 Claim, 7 Drawing Sheets
